1 Claim

ABSTRACT OF THE DISCLOSURE

There is disclosed a soap dispenser including a housing having a supply of powdered soap therein, a slide disposed below the powdered soap, which slide may be drawn from a first position in which it is filled by a charge of soap falling from the supply thereof, into a second position in which the charge of soap is emptied into a distributing orifice, resilient structure tending to return the slide into its first position whenever it is shifted therefrom, and timing mechanism preventing the return of the slide from its second position back into its first position until the expiration of a predetermined period of time following the dispensing of a charge of soap.

The present invention relates to soap dispensers, and particularly to soap dispensers including mechanism causing a predetermined time interval between dispensing operations of the soap dispenser.

It is an important object of the present invention to provide a soap dispenser comprising a housing having thereon a supply of soap in powdered form, a slide mounted in the housing below the soap supply and movable from a first position wherein it is filled by a charge of soap falling from the soap supply to a second position in which the charge of soap is emptied into a distributing orifice, resilient means urging the slide from the second position back into the first position whenever it is shifted away therefrom, and timing mechanism connected to said slide and preventing the return thereof from the second position into the first position until after the lapse of a predetermined period of time, thereby to assure that only a single charge of soap is dispensed during the predetermined period of time.

Another object of the invention is to provide a soap dispenser of the type set forth wherein the timing mechanism is a pair of suction cups mounted respectively upon the housing and the slide, the suction cups serving to hold the slide in the second position when engaged and having an orifice that bleeds air thereinto at a predetermined rate, thus to provide a timing of the release of the suction cups from each other.

In connection with the foregoing object, another object of the invention is to provide an adjustment for the orifice, thereby to adjust the time interval during which the slide is held in the second or discharge position thereof.

Another object of the invention is to provide in a soap dispenser of the type set forth a push rod for the slide that is readily available to a user for moving the slide between the first and second positions thereof.

These and other objects of the present invention, together with its numerous advantages, will be apparent from the following description of a preferred embodiment thereof, taken with the accompanying drawings, in which:

FIGURE 1 is a front elevational view of a soap dispenser made in accordance with the present invention;

FIG. 2 is a rear view of the soap dispenser of FIG. 1;

FIG. 3 is a bottom view of the soap dispenser of FIGS. 1 and 2;

2

FIG. 4 is a view in vertical section along the line 4—4 of FIG. 1;

FIG. 5 is a side elevational view with certain portions broken away and showing the parts in the dispensing position thereof;

FIG. 6 is a view in vertical section along the line 6—6 of FIG. 4;

FIG. 7 is a view in horizontal section along the line 7—7 of FIG. 4; and

FIG. 8 is a view in horizontal section along the line 8—8 of FIG. 4.

The illustrated device comprises a plastic housing consisting of two pieces or parts 1 and 2, piece 1 being designed to be attached to a wall by its rear side 1a, and the other piece 2 being removably bolted to the piece 1 by means of a lock 3. The part 1 has on its lower face a snout or discharge 4 creating a hopper 4' by which the soap that has previously been abstracted from a cartridge 5 (preferably formed of plastic) is dispensed to the user by the actuation of a control handle 6, as will be described in the following.

The level of soap in the cartridge 5 may be checked by observation through a window 7 arranged in the wall of part 2 of the device (FIGS. 1 to 3). This cartridge 5

is attached by its lower part which has the shape of a truncated pyramid, to two tubes 8 and 9, projecting to the bottom of a recess 10 having a shape corresponding to that of the lower end of the cartridge 5, the member in which is formed the recess 10 being supported by the

upper surface of an intermediary enclosure 11 placed on a board 12 which is attached to the bottom of the body of this device by two parallel laths 13a and 13b (FIGS. 6 and 8). This board 12 has an aperture 12a arranged in alignment with the passage 11a of the enclosure 11 by

which the soap powder contained in this enclosure 11 can descend by gravity through the aperture 12a into a slot 14a which is created by a slide 14 mounted slidably within the seat defined by the laths 13a and 13b, the board 12 and the bottom of the body part 1 of the apparatus.

The slide 14 is constituted by a rectangular board having on its rear side a lug 15a providing a support for a suction cup 15. The slide 14 is able to occupy two distinct position illustrated in FIGS. 4 and 5, i.e., a first retracted or charging position, in which the slot 14a is aligned with the passage 11a of the enclosure 11, and a second advanced position or discharging position (FIG. 5) which this slot 14a extends above the opening of the snout 4.

The slide 14 is acted upon by two springs 16a and 16b attached at both sides of the suction cup 15 around a common axis 16 extending between the wings of a stirrup 17 integral by its intermediary part with a vertical board 18 attached on the enclosure 11.

One of the ends of the springs 16a and 16b bears against a strip 17a of the stirrup 17 and the other end against the lug attached to the foot of the suction cup 15. These springs 16 and 17 tend to maintain the slide 14 in its retracted position (FIG. 4) or to return it there in case that it has been shifted to its discharge position (FIG. 5).

Arranged opposite the suction cup 15 and mounted upon the housing part 1 is another suction cup 19, the suction cup 19 including a tubular piece 19a having a passage therethrough within which is disposed an adjustable metal valve 19b. By moving the metal valve 19b inwardly and outwardly with respect to the passage in the tubular piece 19a, the rate of flow of air through the passage in the piece 19a may be adjusted.

When the slide 14 is in the charging position illustrated in FIG. 4, the suction cups 15 and 19 are spaced away from each other, but when the slide 14 is moved

to the discharge position thereof illustrated in FIG. 5, the suction cups 15 and 19 are pressed firmly one against the other. The suction cups 15 and 19 are formed of rubber or other suitable elastic material and therefore compress and serve to force the air from therebetween in a well-known manner; once the suction cups 15 and 19 have been firmly pressed together, they will be held in that position by the pressure of the atmosphere acting on the outer surfaces thereof until such time as the chamber formed therebetween has admitted thereto sufficient air. The only source of air for admission to the chamber between the suction cups 15 and 19 is through the passage in the piece 19a, and the flow of air through the passage is in turn controlled by the position or adjustment of the valve 19b therein. Depending upon the position of the valve 19b, sufficient air is admitted into the chamber between the suction cups 15 and 19 after a predetermined time interval so that the springs 16a and 16b can move the slide 14 and the attached parts from the discharging position illustrated in FIG. 5 to the charging or retracted position illustrated in FIG. 4.

The rate of admission of air into the chamber between the suction cups 15 and 19 is adjustable as explained above by adjusting the valve 19b. Accordingly it is possible to adjust the time that the slide 14 is held in the discharge position illustrated in FIG. 5 before the return thereof to the charging position illustrated in FIG. 4. During this predetermined time interval, the user can obtain only a single charge of soap, which charge of soap should be adequate for the washing operation, whereby the user is discouraged from needlessly wasting soap by a multiple actuation of the slide 14.

The control of the shifting of the slide 14 from its position illustrated in FIG. 4 into that illustrated in FIG. 5 is effected as described by the displacement of the handle 6 from the right to the left side in FIG. 4 against two springs 20a and 20b attached around the axis 16, as are the springs 16a and 16b. These springs 20a and 20b at one end bear against an arm of the strip 17a of the stirrup 17 and at the other end bear against a bar 20 (FIGS. 4 and 7) integral with a push rod 21 to which the handle 6 is attached. The push rod 21 is formed by a strip cut in the shape of a U in the opening of which the lug 14a of the slide 14 is engaged.

From the above description, it may be understood that the movement from right to left (FIG. 5) of the handle 6 produces a corresponding displacement of the slide 14 into its position illustrated in FIG. 5, and that the slide 14 tends to be maintained in this position by the action of the suction cups 15 and 19, even if the handle and the push rod 21, which is associated with it, are returned to the right by the action of the springs 20a and 20b.

A second actuation of the handle 6, when the two air suction cups 15 and 19 are attached to each other, could not do else but maintain the cups stuck together and delay the instant when the slide 14 is able to return into the position of FIG. 4 to receive a new charge of soap powder.

It will be mentioned also that in order to enhance the flow of the powdered soap into the intermediate enclosure 11, the tubes 8 and 9 have their lateral surfaces cut off in 8a and 9a (FIG. 6). In a complementary way,

the bottom of the recess 10 of the enclosure 11 is pierced by small openings 10a surrounding the tubes 8 and 9.

The volume of the enclosure 11 is sized in order to create a reserve of powder corresponding to 25 or 30 charges for the slide 14.

While there has been described what is at present considered to be the preferred embodiment of the invention, it will be understood that various changes and modifications may be made therein and it is intended to cover in the appended claims all such changes and modifications.

What is claimed is:

1. A manually operable soap dispenser comprising a housing having in the upper portion thereof a powdered soap storage compartment and having in the lower portion thereof a soap discharge opening, a slide mounted in said housing below said compartment and slidably movable between a charging position and a discharging position, said slide in the charging position thereof being disposed below said compartment for receiving a charge of soap therefrom, said slide in the discharging position thereof being in registry with said discharge opening to discharge the charge of soap therethrough, first means resiliently urging said slide into the charging position thereof, a manually operable handle slidably mounted in said housing and movable between a first position and a second position, said handle in the first position thereof being in position to engage said slide when said slide is in the charging position thereof, said handle while engaging said slide being manually movable from its first position to its second position to move said slide from its charging position to its discharging position, second means resiliently urging said handle into the first position thereof, and timing mechanism mounted in said housing and operatively connected to said slide and operative to hold said slide in the discharging position thereof against the action of said first resilient means for a predetermined time interval after sliding movement of said slide to its discharging position, said handle being slidably movable in said housing independently of said slide so that movement of said handle during said predetermined time interval does not move said slide between its charging and discharging positions, thereby to assure that only a single charge of the soap is dispensed by said dispenser during said predetermined time interval.
